UNITED STATES PATENT OFFICE

MICHAEL MAES, OF CINCINNATI, OHIO

FOLDING TABLE AND BENCH

Application filed August 10, 1928. Serial No. 298,674.

This invention relates to a folding bench and in particular, to that type which is hinged at its end in a stationary position or to a stationary article, such as a cabinet, and which can be perpendicularly folded to occupy a minimum of space.

An object of the invention is to provide a device of the class described which is simple, inexpensive and efficient.

Another object is to provide such a device with an improved co-operation of parts as regards its use with a cabinet.

These and other objects are attained by the means described herein and illustrated in the accompanying drawings, in which:

Fig. 1 is a plan view of the under side of the bench in a folded position and mounted upon the inner side of a cabinet door.

Fig. 2 is a view on line 2—2 of Fig. 1.

Fig. 3 is a side elevational view of the bench in its operative position and mounted as in Fig. 1.

Fig. 4 is a view on line 4—4 of Fig. 3.

Fig. 5 is a view on line 5—5 of Fig. 4.

The bench as herein shown is particularly adapted for use with a so-called "combination set" in which a table and side benches are hinged to and capable of being folded up within a cabinet. The table is usually hinged within the cabinet proper and the benches similarly secured to the inner side of the cabinet doors, so that all three can be enclosed and hidden from view within the cabinet when not in use.

Wood is the material preferably used in making the bench. Seat member 8 has supports 9 and 10 hinged to its under side. Supports 9 and 10 have legs 11 and apertures 12 and 13 at their lower ends, aperture 13 being cut more deeply than aperture 12. Offset

hinges 14 secure support 9 to the under side of seat member 8 adjacent one end thereof. Hinges 15 similarly secure support 10 to seat member 8 adjacent the opposite end thereof.

A link member 16 extends longitudinally between supports 9 and 10. The link member 16 is connected by the offset hinge 17 to the inner face of support 9, immediately above aperture 12. The opposite end of link member 16 is secured by the offset hinge 18 to the

upper edge of aperture 13. One leaf on hinges 17 and 18 is L-shaped and so fixed upon link member 16 as to support the latter when the bench is lowered.

The bench as shown is mounted upon a cabinet door 19. Spaced transverse blocks 20 and 21 are secured upon the inner side of door 19 adjacent the lower end thereof. Spaced vertical rods 22 are fixed between the block 20 and the block 21. Bearings 23, 55 60 reciprocally mounted upon rods 22, are fixed to the outer face of support 9.

Ends 24 and 25 of seat member 8 are rounded off along their upper transverse edges. End 24 overhangs block 20 when the bench is lowered. Upon raising of the bench, end 24 seats upon block 20 and further upward movement of seat 8 actuates support 9 upwardly upon the slideable bearings 23. The beveling of end 24 prevents hindrance that would otherwise occur in the leverage action just described.

In the folded bench, shown in Figs. 1 and 2, seat 8 lies adjacent door 19, end 24 being seated endwise upon block 20 and supports 9, 75 80 85 and 10 hang downwardly from seat 8 with link member 16 lying in the plane just outside that of the supports. The lower end of support 9, it will be seen, is held well above its normal contact point with the floor.

A suitable latch member 26 is so placed upon door 19 as to co-operate with seat 8 in retaining the bench in a folded position against door 19. Seat 8 is supplied with handle 27.

It is to be noted that the use of longer bearings 23 and a greater spacing of hinges 14 from end 24 will permit support 9 to be raised to a greater height, when the bench is folded.

The fact is likewise to be emphasized that a comparatively light and unsubstantial structure, such as a hinged cabinet door, is enabled to support a comparatively heavy structure such as the bench. A bench when in use is wholly self-supporting, depending for this in no wise upon the door. And when the bench is folded up its weight is nicely distributed so that no undue strain results.

What is claimed is:

1. In combination with a suitable mounting, a foldable bench comprising a seat member, supports pivoted thereon, a link pivoted to and connecting the supports, perforate bearings fixed upon one of the supports, blocks fixed upon the mounting, one of the blocks being positioned beneath and adjacent an end of said seat member, and rods fixed between the blocks and passing through said perforate bearings.
2. In a bench adapted to be vertically folded against a suitable mounting, the combination with such mounting of a seat member, supports hinged thereto, blocks on the mounting, vertical rods held by the blocks, and bearings on one of the supports and reciprocable upon the rods, said seat member being positioned so that one end overhangs the blocks, said end being rounded to clear the mounting upon folding of the bench.
3. The combination with a mounting member, of a collapsible bench comprising a seat member, a pair of support members pivotally mounted at the ends of the seat member and a link between the support members and pivotally connected at its ends to one each of the support members whereby the support members and link may be collapsed relative the seat for positioning the supports and link in substantial parallelism with one another and adjacent to and in substantial parallelism with the seat, the said hinged connections adapted to permit movement of the support members to substantially perpendicular positions relative the seat and link, and means for mounting the bench on the mounting member for vertical movement of the bench relative the mounting member when collapsing and extending the bench relative the mounting member, whereby the bench is raised relative the mounting member when the bench is moved to collapsed position, and whereby the bench is lowered relative the mounting member when moved to extended position and whereby the seat in extended position is supported solely by the support members and the mounting member is relieved of all weight disposed upon the extended bench.
4. The combination with a cabinet, of a door pivotally mounted on the cabinet to move about a vertical axis to opened and closed positions relative the cabinet, and a collapsible bench mounted on the inner face of the door, the bench comprising a seat member, a pair of support members pivotally mounted at the ends of the seat member and a link between the support members and pivotally connected at its ends to one each of the support members whereby the support members and link may be collapsed relative the seat for positioning the supports and link in substantial parallelism with one another and adjacent to and in substantial parallelism with the seat, the said hinged connections adapted

to permit movement of the support members to substantially perpendicular positions relative the seat and link, and means for mounting the bench on the door for vertical movement of the bench relative the door when collapsing and extending the bench relative the door, whereby the bench is raised relative the door when the bench is moved to collapsed position and whereby the bench is lowered relative the door when moved to extended position and whereby the seat in extended position is supported solely by the support member, and the door is relieved of all weight disposed upon the extended bench.

In testimony whereof, I have hereunto subscribed my name this 30th day of July, 1928.

MICHAEL MAES.
